UNITED STATES PATENT OFFICE.

CHARLES F. FREDE, OF ST. LOUIS, MISSOURI, ASSIGNOR TO COMMONWEALTH STEEL COMPANY, OF ST. LOUIS, MISSOURI, A CORPORATION OF NEW JERSEY.

DOUBLE BODY-BOLSTER.

1,049,693.

Specification of Letters Patent. Patented Jan. 7, 1913.

Application filed June 4, 1912. Serial No. 701,529.

To all whom it may concern:

Be it known that I, CHARLES F. FREDE, a citizen of the United States, residing at St. Louis, Missouri, have invented a certain new and useful Improvement in Double Body-Bolsters, of which the following is a full, clear, and exact description, such as will enable others skilled in the art to which it appertains to make and use the same, reference being had to the accompanying drawings, forming part of this specification, in which—

Figure 1 is a plan view of a double body bolster of my improved construction. Fig. 15 2 is a vertical section taken on the line 2—2 of Fig. 1. Fig. 3 is a vertical section taken on the line 3—3 of Fig. 1.

This invention relates to a double body bolster for railway cars of the type shown 20 in patents #706,646 and 706,680.

The principal objects of my invention are, to provide a one-piece cast metal body bolster wherein the two main carrying members are provided at their centers with openings 25 adapted to receive the center sills of the car underframe, to connect the central portions of the main carrying members with a member that is substantially U-shaped in cross section that forms a support for the center 30 sills, and further to produce a comparatively light, strong, durable and rigid structure having its component members so arranged and the metal therein so distributed as to readily withstand all strains and 35 stresses to which the structure may be subjected in service.

To the above purposes my invention consists in certain novel features of construction and arrangement of parts hereinafter more 40 fully described and claimed.

In the construction of the double body bolster as shown 1 designates the main carrying members which are arranged parallel with each other, said members being preferably of I-beam shape in cross section and with their ends formed so as to receive the side sills of the car underframe. Formed through the central portions of the webs of these members 1 are openings 2, and to 45 reinforce the bottom flanges of the members beneath these openings, longitudinally extending ribs 3 are formed on the undersides of said bottom flanges beneath said openings.

Formed integral with and connecting the 50 central portions of the members 1 is a

trough-shaped housing comprising a bottom plate 4 and a pair of vertically disposed walls or web plates 5. The bottom plate 4 is in alignment with and practically a continuation of the bottom flanges of the members 1, and the vertical walls of web plates 5 are arranged at the end of the openings 2. By such construction a member that is substantially U-shaped in cross section unites the central portions of the members 1 and 55 forms a support and housing for the center sills A of the car underframe. If desired the bottom plate 4 may be provided with openings 6, and formed integral with the underside of said bottom plate at the inner 60 ends of these openings are transversely disposed strengthening ribs or flanges 7. Formed integral with the upper edges of the vertical walls or web plates 5 are horizontally disposed strengthening flanges 8, the 65 ends of which unite with the top flanges of the members 1.

Side beams 9, preferably channel-shaped in cross section, are arranged between the outer portions of the main carrying members 1, which side beams are parallel with the central member of the double body bolster and carry the side bearings.

Formed through the center of the bottom plate 4 is an opening 10 adapted to receive 85 the lower portion of the king pin (not shown), and which king pin passes through a cast metal housing B that is arranged between the center sills. Fixed in any suitable manner to the underside of the plate 4 between the flanges or strengthening ribs 7 is a center bearing plate C, provided with a centrally arranged opening that coincides with the king pin openings through the plate 4 and the housing B.

In my improved double body bolster the main carrying members that are provided with openings at their centers for the center sills, are united by a trough-shaped member, which, besides forming a strong and rigid connection between the centers of the main carrying members, provides a support for the center sills and for the cast metal housing arranged between said center sills and which receives the king pin.

The top and bottom flanges of the main carrying members are continuous above the openings in the central portions thereof, and by connecting the end portions of the channel-shaped member with the main carrying

members around the openings therein, a substantial one-piece structure is produced which has the requisite strength and rigidity to withstand all service strains and stresses 5 to which it may be subjected.

A double body bolster of my improved construction can be readily combined with the center and side sills of an underframe, and these parts can be assembled with the 10 expenditure of comparatively little time and labor.

It will be readily understood that minor changes in the size, form and construction of the various parts of my improved underframe can be made and substituted for those 15 herein shown and described without departing from the spirit of my invention, the scope of which is set forth in the appended claims.

20 I claim:

1. A double body bolster having a pair of main carrying members provided with openings adapted to receive the center sills of a car underframe and a centrally disposed, 25 trough-shaped member integral with said main carrying members.

2. A double body bolster having two main carrying members provided with openings adapted to receive the center sills of a car 30 underframe, and a channel-shaped member connecting the central portions of said main carrying members.

3. A double body bolster having main carrying members having openings formed 35 through their central portions, adapted to receive the center sills of a car underframe, and center sill supports integral with and connecting the central portions of said main carrying members.

40 4. A double body bolster having a pair of main carrying members that are provided with top and bottom flanges, and with center sill openings through their central portions between said flanges and a centrally disposed, 45 trough-shaped member integral with and connecting said main carrying members.

45 5. A double body bolster having a pair of main carrying members that are provided

with top and bottom flanges, with center sill 50 openings through their central portions between said flanges, reinforcing ribs on the bottom flanges beneath the center sill openings and a centrally disposed, trough-shaped member connecting said main carrying 55 members.

6. A cast metal body bolster provided with center sill openings in its main carrying members, and a channel-shaped member connecting the central portions of said 60 main carrying members.

7. A double body bolster having a pair of main carrying members provided with centrally arranged center sill openings, vertically disposed walls integral with the main 65 carrying members at the ends of the center sill openings, and a bottom plate connecting the lower portions of said walls.

8. A double body bolster having a pair of main carrying members provided with center sill 70 openings, and a center sill supporting plate integral with the central portions of said main carrying members beneath the center sill openings.

9. A double body bolster having main 75 carrying members provided with center sill openings, and flanged plates integral with and connecting said main carrying members, which flanged plates are arranged at the ends of the center sill openings. 80

10. In a double body bolster, a pair of main carrying members provided with center sill openings, a channel-shaped member connecting the central portions of said carrying members, and side rails connecting 85 the outer portions of said carrying members.

11. A double body bolster having a pair of main carrying members, and a trough-shaped center sill supporting member integral with and connecting the central portions of said main carrying members. 90

In testimony whereof I hereunto affix my signature in the presence of two witnesses, this 20th day of May, 1912.

CHARLES F. FREDE.
